CLAIM

(**) **Term:** **15 Years**

The ornamental design for a protective cover for a switch on a power strip, as shown and described.

DESCRIPTION

(21) **Appl. No.:** **29/757,071**

FIG. 1 is a perspective view of a protective cover for a switch on a power strip showing our new design;

(22) **Filed:** **Nov. 3, 2020**

FIG. 2 is a front elevational view thereof;

(51) **LOC (13) Cl.** **13-03**

FIG. 3 is a rear elevational view thereof;

(52) **U.S. Cl.**

FIG. 4 is a left elevational view thereof;

USPC **D13/156**

FIG. 5 is a right elevational view thereof;

(58) **Field of Classification Search**

FIG. 6 is a top view thereof;

USPC D13/155, 156, 110; D8/353, 356
See application file for complete search history.

FIG. 7 is a bottom view thereof;

(56) **References Cited**

FIG. 8 is a perspective view of the protective cover for the switch on the power strip viewed from another direction;

U.S. PATENT DOCUMENTS

FIG. 9 is a cross-sectional view taken along line 9-9 of FIG.

6;

FIG. 10 is a cross-sectional view taken along line 10-10 of
